UNITED STATES PATENT OFFICE.

ISADOR EARLE LOEWENBERG, OF CONVERSE, INDIANA.

BASKET-HANDLE.

1,310,356.

Specification of Letters Patent. Patented July 15, 1919.

Application filed September 14, 1916, Serial No. 120,085. Renewed April 7, 1919. Serial No. 288,220.

To all whom it may concern:

Be it known that I, ISADOR E. LOEWENBERG, a citizen of the United States, residing at Converse, in the county of Miami and 5 State of Indiana, have invented certain new and useful Improvements in Basket-Handles; and I do declare the following to be a full, clear, and exact description of the invention, such as will enable others skilled in 10 the art to which it appertains to make and use the same.

This invention relates to new and useful improvements in handles, and more particularly to handles which are applicable to 15 baskets. The primary object of the invention is to provide a basket handle that is formed of a stiffened fabric and which is securely fastened between the basket rims, but will not interfere with the proper nest- 20 ing of the baskets when they are being shipped.

Another object of the invention is to provide a flexible fabric handle of this character for baskets that will not warp or contract, 25 and which will be securely fastened to the rims of the basket in such a manner that it will not pull away from the same.

Another object of the invention is to provide a device of this character which is easily 30 and simply constructed, inexpensive to manufacture, and one which will be very efficient in operation.

With these and numerous other objects in view my invention consists of the novel 35 features of construction, and the combination and arrangement of parts which will be hereinafter referred to and more particularly pointed out in the specification and claim.

40 In the accompanying drawings:—

Figure 1 is a side elevation of a portion of a basket showing my handle applied thereto;

Fig. 2 is a vertical section taken on the line 2—2 of Fig. 1;

45 Fig. 3 is a horizontal section taken on the line 3—3 of Fig. 1; and

Fig. 4 is a detail perspective of one of the fillers.

In describing my invention I shall refer 50 to the drawings in which similar reference characters designate corresponding parts throughout the several views and in which the numeral 1 represents a portion of a basket of the ordinary type, being provided 55 with hoop rims 2 between which are adapted to be secured the ends of the handle.

My improved handle is primarily formed of a slightly flexible strip of fabric material which is designated by the numeral 3, and this strip, as shown in the drawings, is 60 formed of corded webbing, the cords 4 being covered by the webbing and extending longitudinally with respect to the same. The handle when in use is twisted substantially U-shaped as clearly shown in Fig. 1 65 of the drawings, and the arm portions 5 of the same are extended downwardly between the rim hoops of the basket.

The portions of the arms which are extended between the rim hoops are securely 70 held into engagement therewith by fastening means 6 which in this instance consists of nails that extend through the rim hoops and the adjacent portions of the strip. These nails are placed at spaced intervals 75 and are disposed in staggered relation and the inner ends of the same are bent back upon themselves as clearly shown in Fig. 3 of the drawings. This fastening means would ordinarily be sufficient to hold the 80 handle securely engaged with the basket, but I have provided additional fastening means to prevent the handle from becoming detached should any undue strain be placed 85 upon the same.

This additional fastening means consists in so wrapping the lower ends of the end portions of the handle that extend beneath the rim hoops so as to form enlarged heads 7 on the same, that will not be able to pull 90 through the rim hoops, should the nails become disengaged. These enlarged heads 7 are formed first by bending the lower portions of the arms outwardly and downwardly as shown at 8, then inwardly and upwardly 95 as shown at 9 to form a loop, and finally downwardly between the first mentioned downwardly extending portions and the upwardly extending portions as shown at 10. The extremities of the arms are spaced a 100 short distance above the interior sides of the loops 9, and in these spaces are disposed twisted cord fillers 11, around which primarily the lower ends of the arms are wrapped. The enlarged heads 7 on the 105 lower ends are held in this position, which is clearly illustrated in Fig. 2 of the drawings, by wire stitching 12 which passes transversely therethrough and holds the same securely into engagement.

110 By the use of these enlarged heads it will be obvious that it will be impossible for

the handle to become disengaged from the basket as they form additional securing means in addition to the nails through the rim hoops. Owing to the fact that the handle is formed of a flexible fabric, the same will not interfere with the baskets when they are piled one upon the other, thus reducing the room necessary in shipping and storing the baskets. There will be absolutely 10 no likelihood of breakage of this handle, as the same will easily bend and may be at once placed into operative position.

From the foregoing description of the construction and operation of my improved 15 handle for baskets, the manner of applying the same to use and the operation thereof will be readily understood, and it will be seen that I have provided a simple and efficient means for carrying out the objects of 20 the invention.

I claim:—

In combination with a basket, a handle attached to the rim thereof and consisting of a strap of flexible material bent into substantially U-shape to provide a grasping 25

portion and two depending arms, said arms being passed downwardly between the rim hoops and provided with enlarged heads positioned below the latter, said heads being formed by bending said depending arms first outwardly and downwardly, then inwardly and upwardly to provide loops, and finally downwardly between the first mentioned downwardly and upwardly extending portions, the extremities of the last mentioned downwardly extending portions being spaced slightly above the interior sides of said loops, fillers extending through said heads being disposed in the spaces between the extremities of said arms and the interior sides of said loops, and stitching passing said heads.

In testimony whereof I have hereunto set my hand in the presence of two subscribing witnesses.

ISADOR EARLE LOEWENBERG.
